(No Model.)

G. KER.
CAR COUPLING.

No. 520,928.

Patented June 5, 1894.

UNITED STATES PATENT OFFICE.

GEORGE KER, OF PORTLAND, OREGON, ASSIGNOR TO THE WESTERN AUTOMATIC CAR-COUPLING COMPANY, OF SAME PLACE.

CAR-COUPLING.

SPECIFICATION forming part of Letters Patent No. 520,928, dated June 5, 1894.

Application filed December 27, 1892. Renewed October 31, 1893. Serial No. 489,663. (No model.)

To all whom it may concern:

Be it known that I, GEORGE KER, a citizen of the United States, residing at Portland, Multnomah county, and State of Oregon, have 5 invented a new and useful Improvement in Car-Couplings, of which the following is a specification, reference being had to the accompanying drawings, forming a part hereof.

My invention relates to car-couplings of the drop-hook class, intended to couple automatically, and it is my object to obtain a durable and simple coupling, operating on the principle mentioned, but better adapted to that purpose than the couplings heretofore in use. 10 Among others, one of the principal features of my invention is to adapt my coupling hook and drawhead to lock with each other while the cars are in motion, to prevent the coupling from becoming disengaged, without interfering with the uncoupling of cars. And to attain greater durability the construction of my drawhead and coupling hook is such as to distribute the pull of the link on the coupling-hook between three bearings, as will 15 appear from the accompanying drawings, above referred to, in which the figures seen show as follows:

Figures 1 and 2 are vertical sections. Fig. 3 is a top view. Fig. 4, shows means for lifting my coupling hook, to uncouple; and Fig. 5 shows my coupling hook.

Like letters refer to like parts throughout the several views.

The drawhead A, has a top-opening b, extending downward and connecting in front with the throat c, and in the rear with the sockets or boxes d, which receive the short journals or trunnions e of the hook f. The sockets d, open out on top of the drawhead, 35 their mouths being so constructed as to facilitate the insertion of the said trunnions e of the hook f; and the front sides of the sockets d are provided with concave recesses g leaving abutments h, such construction affording bearings for the trunnions of the hook, under certain conditions, as will be seen. The bottom of the drawhead is provided with a slot or opening i to discharge dirt or snow that may fall through the opening b, and 40 which might otherwise collect in the drawhead and interfere with the working of my

coupling hook; and j is another annular opening intended to receive the nose f' of the hook, but being also adapted to receive the lower end of a coupling pin, which could, in an emergency, be substituted for my coupling hook. The drawhead is bell mouthed to facilitate the insertion of a coupling link, k.

The construction of my coupling hook f is shown in Fig. 5. When the same is inserted 60 in the top of my drawhead the short journals or trunnions, e, will rest on the bottom of the sockets d and the base of the hook rest on the floor of the opening b, the rear portion of said hook being enlarged so that the bottom 65 thereof, when resting in the position mentioned will overlap the slot i. While in this position my hook is ready to receive the coupling link. The latter being engaged in the drawhead of one car, and such car backed 70 against another to be coupled, the link enters the mouth of the drawhead and in so doing is brought in contact with the nose of the hook, causing said hook to lift and permit the link to pass, and then dropping in place again 75 in the same position that it first occupied, indicated in Fig. 1, by a broken outline of such hook. If the cars are now started the pull of the link will draw the hook forward, bringing the trunnions e, against the abutments h, 80 the head, l, of the hook in contact with the abutment l', in the drawhead, and dropping the nose in the opening j. Thus, not only will there be a central pull of the link on the hook, but the strain on the hook itself will be 85 distributed between three points of contact,—the trunnions, the head and the nose. When uncoupling the cars, as the same are jammed together the link is driven against the neck 90 of the hook, causing the latter to assume its original, unlocked position, and the hook may then be raised by means of a chain and lever, shown for example in Fig. 5, or other contrivance, to disengage the coupling link. To provide convenient means for holding the lever 95 m, by means of which my hook is lifted, I have cut part of the bearing n away, so that the lever when raised can be secured by pushing the same over the lower tube-portion left intact of said bearing n.

In Fig. 2 I have shown the coupling-hook in position to hold a link so as to couple with

the drawhead of a car standing lower off the ground, the nose f' having a concave recess to rest on and hold the link for this purpose in the desired position.

5 Having thus described my invention, now what I claim, and desire to secure by Letters Patent, is—

1. In a car-coupling, a drawhead having an opening as b extending downward and connecting in front with the throat of the drawhead, and in the rear with sockets d , adapted to receive the short journals or trunnions e of the hook, the said sockets opening out on top of the drawhead and having concave recesses

15 leaving abutments h for the trunnions of the hook to bear against when the coupling link pulls on the same in combination with a coupling hook, constructed substantially as described having trunnions adapted to be seated

20 in said sockets d , and means for lifting said hook when uncoupling, substantially as set forth.

2. In a car-coupling, a drawhead having an opening as b extending downward and connecting in front with the throat of the drawhead, and in the rear with sockets d , adapted to receive the short journals or trunnions e of the hook, the said sockets opening out on top of the drawhead and having concave recesses

25 leaving abutments h , for the trunnions of the hook to bear against when the coupling link pulls on the same, and abutments l' for the head of the hook to bear against and lock with as specified, in combination with a coupling

hook constructed substantially as described, 35 having trunnions adapted to be seated in said sockets, d , and the head of which hook is adapted to lock with the said abutments l' in the drawhead, and means for lifting said hook when uncoupling, all substantially as de- 40 scribed.

3. In a car coupler, a drawhead having an opening b extending downward and connecting in front with the throat of the drawhead, and in the rear with the sockets d , adapted to 45 receive the short journals or trunnions e , of the hook, the sockets d opening out on top of the drawhead, and having concave recesses g , leaving abutments h for the trunnions of the hook to bear against when the coupling- 50 link draws on the same, an abutment l' , for the head of the hook to bear against and lock with, as specified, and a slot i and annular opening j for the purposes mentioned, in combination with a coupling hook, constructed 55 substantially as described, having trunnions adapted to be seated in said sockets d , and the head thereof being adapted to lock with the abutment l' , in the drawhead as described, and means for lifting said hook when uncoupling, all substantially as set forth.

In witness whereof I have hereunto affixed my signature in the presence of two witnesses.

GEORGE KER.
